John Deinard
ATTORNEY

UNITED STATES PATENT OFFICE.

GEORGE ADSIT, OF PATERSON, NEW JERSEY, ASSIGNOR TO BENJAMIN EASTWOOD COMPANY, OF PATERSON, NEW JERSEY, A CORPORATION OF NEW JERSEY.

QUILLING MACHINE.

Application filed January 30, 1926. Serial No. 84,877.

This invention relates to machines for winding yarn or thread into the form of compact packages (as for use in shuttles), commonly known as quilling machines. One of the principal objects is to obtain increased production by increasing the winding speed and to this end instead of obtaining the traverse necessary in winding this class of packages from a rocker arm I utilize a barrel cam in a novel way to be indicated, thus avoiding the vibration which is characteristic of a rocker arm or equivalent and is an obstacle to high speed. Another object is to improve the means for establishing and disestablishing the connection between the main rotary driving element and the rotary means driven thereby. Another object is to provide for a nice adjustment, one toward the other, as between the package spindle and the rotary friction wheel forming part of the thread-guiding mechanism. Another object is to construct the machine so that when automatic stopping is effected the "burning" of the package may be avoided. Another object is to provide for lubrication which shall be at once adequate and avoid deposit of the lubricant on exposed parts.

I show in the drawing one complete quilling unit of the machine,

Fig. 1 being a vertical longitudinal section of a quilling unit taken in the plane of the push-rod;

Fig. 2 a plan, a certain shield 41 being removed;

Fig. 3 a vertical section in the plane of line 3—3, Fig. 1, looking forward; and

Figs. 4 and 5 vertical sections in the plane of line 4—4, Fig. 1, and respectively looking forward and rearward.

A support for the working parts is afforded by a generally rectangular housing 1 having a removable cover 1^a and a rearwardly projecting yoke 2 affording a bearing. In the yoke is journaled the drive-shaft 4 carrying a pulley 5 through which, from a suitable belt and substantially after the manner shown for example in my Patent No. 1,457,294, shaft 4 and other rotated parts of the unit are driven. Shaft 4 carries at its inner end, within the housing, the receiving member 6 of a cone-clutch, and it is bored to receive and form a rear bearing for the spindle 7 which is journaled near its forward end in a bearing 8 on the front wall of the

housing; the spindle is reciprocated as well as rotated in these bearings. The spindle has a clutch-member forming the received member of the clutch and movable lengthwise of the spindle (to make and break the clutch) independently thereof but which turns with the spindle—the connection between them being in effect a spline—and comprising a conical head or clutch-member proper 9, the head 10, formed with a peripherally grooved collar 10^a and long pinion 10^b, and two rods 11 rigidly connecting the heads, the mentioned spline-connection between the spindle and head being afforded by a cross-head 12 fixed on the spindle and penetrated by the two rods which slide therein. Shifting of the clutch member last described into or out of engagement with the clutch member 6 of course results in the spindle being rotated by the drive-shaft or left free thereof. For effecting this shifting there is a fork 13 engaged with the collar 10^a and having its sleeve or barrel 13^a slideable on the push-rod 14, being normally urged rearwardly and so tending to hold the clutch engaged by a spiral spring 15 coiled about the push-rod and interposed between said sleeve and a bearing 16 for the push-rod, which also has a bearing in the front wall of the housing; when the push-rod moves forward a collar 14^a thereon encounters the sleeve and retracts the fork (to break the clutch), but when the push-rod is repressed spring 15 becomes active to yieldingly hold the received against the receiving clutch member. The push-rod is capable of rocking slightly in its bearings and has a bell-crank lever 17 fixed thereon, one arm 17^a of which limits this rocking by being interposed between a fixed stop 18 and one side of the housing, said stop having a stop-shoulder at 18^a. The push-rod is normally held pressed forward and also rotatively in the direction to bear laterally against the stop by a combined tension and torsion spring 19 which is coiled about it and secured thereto by the screw 19^a and also to the bearing 16, said spring being stronger than spring 15. When the push-rod is repressed by means of its knob 14^b and to the limit afforded by contact of a collar 14^c thereon with housing a spring 19 turns it and it becomes locked by engagement of its lever arm 17^a with the stop-shoulder of the

stop, and this establishes the shiftable clutch member in yielding pressure engagement with the other clutch member; when the push-rod is turned to disengage its lever arm 5 from said stop-shoulder the push-rod springs forward and disestablishes the clutch-connection.

A barrel cam 20 is journaled on the spindle between two collars 21 and 22 fixed thereon and receives a stud 23 (having a roller 24 thereon) fixed to the housing. The cam has a gear 20^a and rotary motion is transmitted to said gear and hence the cam from pinion 10^b through a counter-shaft 25 journaled in bearings 25^a and 25^b and having a gear 26 in mesh with 10^b and a long pinion 27 in mesh with 20^a. The gearing is such that the rotary motion imparted from pinion 10^b to the cam is suitably less than that of the rotary structure including the spindle and received clutch member with the result that the traverse rate of the spindle is less than its revolution rate.

The construction of the thread guiding mechanism may in general follow that set forth in prior patents to me (for example, No. 1178045), that is to say: The thread-guide rod 28, slidable lengthwise in the housing, is adapted to be moved by the rotary threaded rod 29 having a friction-wheel 29^a and a collar 29^b with which a fork 28^a fixed on the rod 28 is engaged; rod 29, due to intermittent contact of the periphery of the friction wheel with the package being wound and reciprocating with the spindle, is intermittently rotated and thus gradually fed forward by having its threading engaged with the peripheral teeth of a peripherally grooved wheel or nut 30 normally held 40 against rotation by friction means, as the spring washer 30^a, but capable of rotating if the rod is forcibly shifted, as in setting it back to start winding anew. This nut device and a companion plain grooved roller 31 which keeps the rod engaged with its teeth (Fig. 5) are journaled in a bracket 32 arranged to slide on two parallel shafts 33 the upper one of which is rotary and threaded, the upper end of the bracket being formed as a nut 32^a engaged with the threading of this shaft; this threaded shaft has a milled knob 33^a for turning it and so adjusting the bracket laterally. Rod 29 passes loosely through a hole 34 (Fig. 3) in the front wall of the housing and it has a bearing in a ball 35 journaled in the upper end of the bracket 36 suitably supported at the front of the housing, such bearing also affording a fulcrum for the rod around which it may be adjusted by turning the threaded shaft 33 to advance nut 32^a one way or the other. After adjustment of the threaded rod lever-fashion (with the ball as the fulcrum) to obtain the desired degree of pressure of the friction wheel against the wind-

ings the parts as adjusted are held securely in position by tightening a screw (Fig. 2) which causes the nut 32^a, which is split, to clamp the threaded shaft. The adjustability of the means (as 32^a) to engage the 70 threading of the rod 29 laterally with the rod is new in the art.

The stopping of the winding when the package is full has heretofore been accomplished in these machines by causing a cone 75 on the threaded shaft to engage an arm or crank on the push-rod and so turn the latter for tripping the same whereby to break the clutch connection. It is desirable to make the tripping as quick and to effect it with 80 as little incidental resistance to the rotation of the threaded rod as possible in order to avoid undue rubbing of the friction wheel against and consequent "burning" of the silk or other material of the package. Hence 85 the arm or crank, here afforded by the arm 17^b of the bell crank lever 17, is equipped with a lever 38, one arm of which (preferably heavier than the other) overhangs the threaded rod and the other the spindle 90 7, and the collar 21 on the spindle is formed as a cone and the rod also has a cone 39. When the rod advances sufficiently its cone 39 engages and tilts the lever more and more until finally a point is reached where in a 95 forward movement of the spindle cone 21 impinges against said lever and elevating it on cone 39 as a fulcrum trips the lever 18. The tripping is thus not only instantaneous but, because of the interposing of a lever 100 (38), the frictional resistance on cone 39 and hence resistance to rotation of the threaded rod and friction wheel are very materially reduced.

The housing forms at its bottom a reservoir for liquid lubricant, whose maximum level is indicated by the horizontal dotted line in Fig. 1, 40 being the lubricant filling inlet. Gear 26 rotates in this lubricant at such speed that it throws the lubricant up against a shield 41 consisting of a plate extending from one side of the housing over and down beside the gearing and secured to the housing by screws 42. The lubricant is splashed by gear 26 against this shield with 110 such force that it is largely sprayed back onto the rest of the gearing, thus keeping all moving parts lubricated. The top portion of the shield slopes backward and downward, so that the excess lubricant clinging thereto by capillary attraction runs backward to then drip back into the reservoir at the rear end of the shield; if the drip were allowed to ensue forward the lubricant would work forward out of the 115 housing, so that the exposed parts would become oily and the product of the winding would be likely to be damaged.

The operation is in general the same as usual in quilling machines in which the 130

thread-guiding means is gradually fed along by rotation, induced by the package, of its threaded rod as the spindle is reciprocated. For starting to wind the push-rod is 5 pressed and becomes locked in the rearward position, thus establishing the clutch-engagement which causes the spindle to be rotated and also, through the gearing, the cam, which, coacting with stud 23 and acting alternately against the collars 21 and 22 on the spindle, reciprocates the latter, the 10 rate of reciprocation being suitably less than the revolution rate of the spindle according to the gearing. When in the advance of the thread-guiding means as the package builds up the lever 38 is actuated as explained to release the push-rod the same in moving forward disestablishes the clutch and stops the winding.

20 Having now described my invention what I claim and desire to secure by Letters Patent are:

1. In combination, a supporting structure, a spindle structure revoluble and reciprocatory therein, and coacting means to reciprocate the spindle structure while rotating one of which is a barrel cam arranged on and concentric and reciprocating with the spindle structure and the other of which is engaged with the camway of said cam and is arranged on the other structure.

2. In combination, a supporting structure, a spindle structure revoluble and reciprocatory therein, and coacting means to reciprocate the spindle structure while rotating one of which is a barrel cam arranged on and concentric and reciprocating with but revoluble independently of the spindle structure and the other of which is engaged with the camway of said cam and is arranged on the other structure.

3. In combination, a supporting structure, a spindle structure revoluble and reciprocatory therein, coacting means to reciprocate the spindle structure while rotating one of which is a barrel cam arranged on and concentric and reciprocating with but revoluble independently of the spindle structure and the other of which is engaged with the camway of said cam and is arranged on the other structure and rotation-transmitting means operatively connecting said spindle structure and cam.

4. In combination, a supporting structure, a spindle structure revoluble and reciprocatory therein, coacting means to reciprocate the spindle structure while rotating one of which is a barrel cam journaled on and arranged on and concentric and reciprocating with the spindle structure and the other of which is engaged with the other structure, and rotation-transmitting means operatively connecting said spindle structure and cam.

5. In combination, a supporting structure, 65 axially alined rotary driving and spindle

members, the latter being longitudinally reciprocatory, a clutch-member on the driving member and a clutch-member splined on the spindle member and movable into and out of engagement with the other clutch-member, and means, including a rotary system driven by the splined clutch member, for reciprocating the spindle member.

6. In combination, a supporting structure, a spindle structure journaled and reciprocatory therein, a rotary member journaled on an axis parallel with the axis of the spindle structure, a rotary cam member journaled on and reciprocating with the spindle structure and geared with the first member, and means on the supporting structure and engaged with the cams to reciprocate the same while rotating and consequently reciprocate the spindle structure.

7. In combination, a supporting structure, a spindle structure journaled and reciprocatory therein, a revoluble member journaled on but fixed against movement lengthwise of the spindle structure and including a cam and a peripherally toothed portion, 90 a rotary peripherally toothed member for driving the first member having its teeth in mesh with said toothed portion and journaled on an axis parallel with the axis of the spindle structure; and means on the supporting structure engaged with the cam and coacting therewith to reciprocate the spindle structure.

8. In combination, a supporting structure, axially alined rotary driving and spindle members journaled therein, a clutch member on one and a clutch member splined on the other of said rotary members and movable into clutch-engagement with the first clutch member, and manually operated means to move the second clutch member into and yieldingly hold the same in clutch-engagement with the other clutch member, said means upon such movement being interlockable with said structure to hold the second clutch member in such clutch engagement.

9. In combination, a supporting means, a spindle structure revoluble and a thread-guiding structure arranged therein, the latter being advanceable, and including an 115 elongated threaded rotary member extending, lengthwise of the spindle structure and having a peripheral contact portion to engage the package being wound and rotate said member, means to reciprocate one structure relatively to the other to cause such engagement, said member being adjustable substantially toward or from the spindle structure, and means, engaged with the thread-ing of said member, for causing advance 125 thereof and hence of the thread-guiding structure on rotation of said member, the last-named means being connected with said member for adjustment therewith.

10. In combination, a supporting means, a

- spindle structure revoluble and a thread-guiding structure arranged therein, the latter being advanceable, and including an elongated threaded rotary member extending, 5 lengthwise of the spindle structure and having a peripheral contact portion to engage the package being wound and rotate said member, means to reciprocate one structure relatively to the other to cause such engagement, said member being adjustable substantially toward or from the spindle 10 structure, means, engaged with the threading of said member and connected with the latter for adjustment therewith, for causing 15 advance of said member and hence of the thread-guiding structure on rotation of said member, and means, having screw-thread engagement with the last-named means, for effecting such adjustment.
- 20 11. In combination, a supporting structure, a spindle member revoluble and longitudinally reciprocatory therein, means to rotate and reciprocate the spindle member, a thread-guiding structure advanceable lengthwise of the spindle member and including a threaded revoluble member having a peripheral portion engageable with the package 45 being wound, means, engaged with the threading of the latter member, for causing advance thereof and hence of the thread-guiding means, cones arranged on one on each of said members, means movable to 50 control the first-named means, and a device on the last-named means and arranged to be engaged by both cones simultaneously and thereby cause movement of the last-named means.
- 25 12. In combination, a supporting structure, a spindle member revoluble and longitudinally reciprocatory therein, means to rotate and reciprocate the spindle member, a thread-guiding structure advanceable lengthwise of the spindle member and including a threaded revoluble member having a peripheral portion engageable with the package 55 being wound, means, engaged with the threading of the latter member, for causing advance thereof and hence of the thread-guiding means, cones arranged one on the threaded and the other on the spindle member, means movable to control the first means, and a device to move the last-named means arranged to be shifted by the first cone into position to be impinged by the second cone.
- 30 13. In a quilling machine, a housing forming at its bottom a liquid reservoir, winding mechanism comprising a system of parts movable in the housing and one of which is revoluble in the lubricant therein on a horizontal axis, and a shield arranged within the housing over the revoluble part and sloping downwardly in a direction lengthwise of the axis of said part.
- 35 14. In a quilling machine, a housing forming at its bottom a liquid reservoir, winding mechanism comprising a system of parts movable in and projecting from one side of the housing and one of which is revoluble in the lubricant therein on a horizontal axis, and a shield arranged within the housing over the revoluble part and sloping downwardly lengthwise of the axis of said part and away from said side of the housing.

In testimony whereof I affix my signature.

GEORGE ADSIT.
